TABLE LIGHTER OR SIMILAR ARTICLE

John Beresford-Evans, Neatham Grange, Alton, England, assignor to Ronson Corporation, Newark, N.J., a corporation of New Jersey

Application September 22, 1958, Serial No. 52,713

Claims priority, application Great Britain June 18, 1958

Term of patent 14 years

(Cl. D48—27)

Fig. 1 is a perspective view of a table lighter showing my new design.

Fig. 2 is a side elevational view of the lighter.

Fig. 3 is an elevational view thereof as seen from the left of Fig. 2.

Fig. 4 is a top plan view of the lighter.

Fig. 5 is a bottom plan view thereof.

Fig. 6 is a detailed elevation on an enlarged scale, showing in more detail the upper ornamental band which appears in Fig. 1, and

Fig. 7 is a view similar to Fig. 6 but showing the lower ornamental band which appears in Fig. 1.

I claim:

The ornamental design for a table lighter or similar article, substantially as shown.
